UNITED STATES PATENT OFFICE.

CYRUS H. SMITH, OF TONICA, ILLINOIS.

GASOLENE-MOTOR RESPIRATOR.

1,135,142.

Specification of Letters Patent. Patented Apr. 13, 1915.

Application filed October 5, 1914. Serial No. 865,165.

To all whom it may concern:

Be it known that I, CYRUS H. SMITH, a citizen of the United States, residing at Tonica, in the county of La Salle and State of Illinois, have invented certain new and useful Improvements in Gasolene-Motor Respirators, of which the following is a specification, reference being had to the accompanying drawings.

10 My invention relates to means providing for the passage of vapor into the cylinders of an internal combustion engine, and particularly to provide means for passing vapor into said cylinders which will prevent the formation of carbon therein, this vapor also being sufficiently moist as to cause the motor to operate in daylight in practically the same manner as at night in a moist atmosphere, this being the condition under which 20 the motor operates most effectively, the power of the engine being increased and the fuel economized by the cleanliness of the cylinders under the action of the vapor and owing to the moist condition of the fuel.

25 A further object of the invention is the provision of a device of this character which is adapted to be connected to the manifold of the engine and whereby a mass of absorbent material may be kept moistened with 30 a liquid of predetermined character and whereby air may be drawn through this mass of absorbent material so as to take up the liquid and carry it into the manifold and so to the several cylinders of the engine.

35 Still another object of the invention is the provision of means whereby the passage of the liquid compound to the chamber containing the absorbent material will be automatically prevented when the engine stops 40 and automatically prevented when the absorbent material is fully saturated, the further passage of said fluid compound, however, being permitted when the predetermined degree of saturation has been lessened or when the device again starts up.

With these and other objects in view, my invention consists in the details of construction and arrangement hereinafter more fully set forth.

50 In order that those skilled in the art to which my invention appertains may under-

stand it, I will proceed to describe the construction and operation of the same, referring by numerals to the accompanying drawings, in which,

55

Figure 1 is a side elevation showing my improved apparatus in place upon an automobile which is shown in broken lines; Fig. 2 is a side elevation on enlarged scale of the apparatus; Fig. 3 is a vertical section 60 partly in elevation and with the connection broken away; Fig. 4 is a cross section on the line *a*—*a* of Fig. 3; and Fig. 5 is a similar view on the line *b*—*b* of Fig. 3.

Similar reference letters indicate like 65 parts in the several figures of the drawings.

1 is a priming cup for the mixture herein-after referred to, the supply from which is controlled by a cock 2, and when delivered it is contained in a font or reservoir 3 from 70 which the contents are conducted through a supply tube 4 provided with a cut off cock 5.

6 is a vent tube leading from the upper end of the font 3 to the lower end of the 75 mixing chamber 7 which is packed with asbestos as clearly indicated at Fig. 3.

The font and the mixing chamber are connected by a threaded and flanged ring 8 between the lower extremity of which and 80 an annular shoulder near the upper end of the mixing chamber are secured two thin sheet brass diaphragms 9 provided with orifices 10, and between these diaphragms is confined two thin brass screens 11.

85

Passing centrally through the diaphragms and screens and through the bottom of the mixing chamber 7, is a tube 12 having a flanged head 13 with a perforated cap 14 between which and the head is confined a 90 screen 15 (see Fig. 5) and the lower end of the tube 12 is secured in position by a flanged nut 16, and connected with the tube 12 is a smaller tube 17, connected as shown at Fig. 2 with a manifold block 18 provided 95 with belt orifices 19.

The manifold block is provided with minute orifices 20 in alinement with the tube 17. The inlets to the mixing chamber from the supply and vent tubes are on opposite 100 sides as clearly shown and to prevent any clogging of the same, a wire screen 21 is

arranged between the asbestos packing and the open ends of the tubes 4 and 6 as clearly shown at Fig. 3.

22 is a flared entrance for atmospheric air whereby a current of air may be drawn through the mixing chamber 7 upon each suction stroke, for the purpose of controlling the amount of air entering through the member 22. This member is provided with 10 a butterfly valve 23 with a controlling arm 24 which is so arranged as to be accessible to the operator, and it is also formed with a well 25 for receiving by gravity any foreign body which may pass the butterfly valve.

It is to be noted that the inlet openings in the head 14 are disposed above the screen 11 so that the air passing into the mixing chamber through the air inlet opening 22 20 must pass through the packing 7 absorbing the liquid with which the packing is saturated and that the air and vaporized liquid will be thoroughly mixed and intermingled by the screen 11 before the air can have access to the perforations in the head 14 and before the air can pass into the manifold. The pipe 6 is for the purpose of normally permitting the liquid contained within the font 3 to flow out through the pipe 4 and 30 into the lower end of the mixing chamber. As the liquid flows out of the pipe 4 air will pass from the mixing chamber by way of the pipe 6 into the upper portion of the font 3, thus keeping the air pressure balanced. 35 If, however, too great a supply of liquid passes through the pipe 4, and as a consequence the liquid in the bottom of the mixing chamber rises so as to close the inlet end of the pipe 6, then the passage of air into the 40 upper portion of the font 3 will be prevented, and as a consequence the liquid in the font 3 will not flow downward through the pipe 4 until the level of the liquid in the mixing chamber has been reduced. Thus 45 when the engine stops the liquid will slowly rise within the lower portion of the mixing chamber until this vent pipe 6 is closed, or if the absorbent material 7 has been thoroughly saturated, then any excess of liquid 50 will gather in the lower portion of the mixing chamber and close up the vent, this action automatically preventing the feeding of liquid to the mixing chamber from the font. As soon as the engine starts up, or as soon 55 as complete saturation of the absorbent material has been lessened the flow of liquid from the font 3 will be again started.

Having described the construction and assembled arrangement of the apparatus, I 60 will now explain the manner in which it is connected in operative relation with an engine.

The block 18 which is arranged between the manifold and the carburetor is secured

in place by removing the bolts employed to 65 connect the carburetor to the intake manifold. The carburetor and the block 18 with suitable gaskets on the inner and outer surfaces is slipped on. The carburetor is readjusted and the bolts are replaced, and it 70 will thus be seen that the intake from the apparatus will be between the carburetor and manifold.

The mixture which I have found especially adapted for use in the font is composed of equal parts of pure glycerin, wood alcohol and hydrogen dioxid for the reason that in the chemical action moisture is obtained from hydrogen dioxid which when broken up forms water and free oxygen. 75 This free oxygen and the breaking up of the alcohol and glycerin form oxidizing agents which have a strong chemical affinity for carbon and with which they combine to form carbon dioxid gas which passes out the 80 exhaust.

From the construction and arrangement shown and described, it will be seen that the asbestos is kept saturated with the compound and that the compound is readily 90 drawn into the engine by the strong air current passing through the butterfly valve and the asbestos and screens.

The several parts can be readily manufactured and assembled, and can also be easily 95 disassembled when necessary, and there is nothing to get out of order as the only part involving motion is the butterfly valve.

All connections between the tubes leading to the font and the mixing chamber are 100 made by the employment of suitable nuts and screw threads.

I do not wish to be confined to the use of any special compound as any compound producing the results named may be used, and 105 likewise I do not wish to be confined to the exact details of construction, dimension, or proportions of the several parts as they may be varied without departing from the principle of my invention which involves the 110 broad idea of arranging a respirator between the carburetor and the manifold.

What I claim as new and desire to secure by Letters Patent is:—

1. A respirator for gasoline motors and 115 adapted to be connected between the carburetor and manifold and comprising a font for a compound; a mixing chamber below the font; a supply tube leading from the font to the mixing chamber; a vent tube 120 leading from the top of the font to the mixing chamber; a valve controlled air receiver communicating with the mixing chamber, and a conduit leading from the interior of the mixing chamber to suitable means for 125 connection between the carburetor and the manifold.

2. In a respirator such as described, and

comprising a font for containing a suitable compound, and a mixing chamber, said font and mixing chamber connected with supply and vent tubes, and an air receiver communicating with the mixing chamber, asbestos packing in the mixing chamber and over the terminals of the supply and vent tubes; a screen confined between thin metal perforated plates secured near the top of the mixing chamber; and a vapor delivery tube having a perforated top above the diaphragms and screen, and means intermediate the vapor delivery tube and the motor adapted to be secured in position between the carbureter and the manifold.

3. In a respirator such as described, and comprising a font and mixing chamber with supply and vent tubes between them, and means for delivering vapor from the mixing chamber; an air receiver communicating with the mixing chamber and provided with a butterfly valve, and means for controlling the butterfly valve.

4. A respirator for gasoline motors, and adapted to be secured in position between the carbureter and manifold, and comprising a filling cup controlled by a cock; a font for containing a moisture producing compound and into which the filling cup opens; a mixing chamber located below the font; a supply tube leading from the bottom of the font to the bottom of the mixing chamber and constricted at its terminal; a screen located between thin metal diaphragms having orifices therein, said diaphragms and screens located near the top of the mixing chamber; a tube having a perforated top and screen therein passing through the diaphragms and screens and bottom of mixing chamber; a flexible tube leading from said tube and communicating with a block through minute orifices in said block; a vent tube leading from the top of the font to the bottom of the mixing chamber; asbestos packing in the mixing chamber and an air receiver having a butterfly valve therein and communicating with the mixing chamber, substantially as and for the purpose set forth.

5. A respirator for explosive engines adapted to be secured in position between the carbureter and the cylinder of the engine, including a font, a mixing chamber into which the fluid from the font is allowed to pass, said mixing chamber having an air inlet, and a conductor leading from the mixing chamber and adapted to be connected to a fuel pipe leading to said engine.

6. A respirator for explosive engines adapted to be connected between the carbureter and manifold, including a font, a mixing chamber into which fluid from the font is allowed to pass, said mixing chamber having an air inlet, a conductor leading from the mixing chamber adapted to be

connected to the fuel pipe leading to the engine between the carbureter and the engine, and means for causing the intermingling of the fluid from the font with the air entering the mixing chamber prior to its 70 passage into said conductor.

7. A respirator for explosive engines including a mixing chamber, a font disposed in conjunction with the mixing chamber and having a conductor leading therefrom 75 into one end of the mixing chamber, said mixing chamber being formed with an air inlet in one side, an absorbent packing in the mixing chamber and adapted to be connected to the manifold of an explosive engine, the inlet opening of said conductor being disposed above the packing.

8. A respirator for explosive engines comprising a font, a mixing chamber, a conductor leading from the lower end of 85 the font into the lower end of the mixing chamber, a vent conductor leading from the lower end of the mixing chamber into the upper end of the font, absorbent material filling the mixing chamber, said mixing 90 chamber having an air inlet in its side wall, a pipe leading from the mixing chamber and extending into the upper portion thereof, the upper end of the pipe being formed with inlet perforations and a screen 95 disposed between the upper end of the pipe and said absorbent material.

9. In a device of the character described, a font, a mixing chamber disposed below the font, a pipe leading from the lower end 100 of the font into the lower end of the mixing chamber, a vent pipe leading from the lower end of the mixing chamber into the upper end of the font, an air inlet pipe leading into the side wall of the mixing chamber, a 105 screen covering the inlet end of the air pipe, and the adjacent ends of the vent pipe and feed pipe, absorbent material packed within the mixing chamber, a screen disposed in the upper portion of the mixing chamber 110 and resting above the absorbent material, and an outlet pipe extending through the bottom of the mixing chamber and up into the space above the screen.

10. A respirator for explosive engines 115 comprising a font, a mixing chamber disposed below the font, a union detachably connecting the mixing chamber and font, a screen supported between the upper end of the mixing chamber and the union and extending across the upper end of the mixing chamber, a feed pipe extending from the lower end of the pipe into the lower end of the mixing chamber, a valve in said pipe, a vent pipe extending from the lower end of 120 the mixing chamber into the upper end of the font, an air inlet pipe entering the side wall of the mixing chamber and provided with a valve for controlling the passage of air therethrough, a screen extending over 130

the openings in the air pipe, vent pipe and
feed pipe, an absorbent packing disposed
within the mixing chamber, a vapor outlet
5 pipe extending through the bottom of the
mixing chamber into the space above the
first named screen and provided with a per-
forated head therein.

In testimony whereof I hereunto affix my
signature in the presence of two witnesses.

CYRUS H. SMITH.
